WATER HEATER

Oran W. Ott, Los Angeles, and Arthur J. Smithers, Alhambra, Calif., assignors to Pacific Pipe & Supply Company, Los Angeles, Calif., a corporation of California

Original No. 1,899,523, dated February 28, 1933,
Serial No. 511,253, January 26, 1931. Application for reissue January 2, 1934, Serial No. 704,920

12 Claims. (Cl. 122—17)

This invention relates to water heaters and particularly to domestic water heaters. In localities where the water contains lime compounds there is considerable difficulty in operating heaters, particularly heaters of the coil type because of the deposit of sulphate or carbonate of lime on the interior of the coil. This deposit or scale materially interferes with the efficiency of the heater in transferring heat to the service water being heated and also materially reduces the effective cross section of the coil, thereby diminishing the amount of water that can flow through the heating coil for delivery at the point where the hot water is to be used. It has been found that the deposits from hard water are greatly increased with the temperature of the plate or surface that is heating the water. In other words, a considerable deposit occurs where a flame or hot gases are located on one side of the heating wall and the water being heated is in contact with the other side of the heating wall.

It has been attempted to overcome these difficulties by constructing a heater with trapped water which comes in contact with the wall that is highly heated by the fire and this trapped water is utilized as a transfer medium for transferring the heat to the service water. In this way the deposit of lime or similar compounds in the service water chamber is greatly reduced. However, if the trapped water is completely confined it may develop a considerable pressure and this would necessitate a substantial increase in the thickness of the plates confining the trapped water. Furthermore, if the construction is such as to permit substantial replacement of the trapped water by the service water during the continued operation of the heater, the depositing of scale will not be prevented.

The general object of this invention is to provide a heater of simple construction which will overcome these difficulties and which is particularly adapted for heating hard waters; also to provide a heater of this type which will be highly efficient in operation and which is so constructed as to maintain equilibrium between the pressure of the trapped water and the service water chamber in which the service water is being heated but without creating a condition that would cause any substantial replacement of the trapped water by the service water.

In other words, water is substantially trapped and is substantially free from replacement by the service water. In this way the deposits in the trapping chamber are greatly reduced.

55 A further object of the invention is to provide

a heater which can be constructed at a low cost which will be efficient in transferring heat to the service water but in which the deposits from the hard water will be reduced to a minimum.

Further objects of the invention will appear 60 hereinafter.

The invention consists in novel parts and combinations of parts to be described hereinafter, all of which contribute to produce an efficient 65 water heater.

A preferred embodiment of the invention is described in the following specification, while the broad scope of the invention is pointed out in the appended claims.

In the drawing:

Figure 1 is a vertical section through a heater embodying our invention with certain parts broken away.

Figure 2 is a horizontal section taken about on the line 2—2 of Figure 1.

Referring more particularly to the parts, in constructing the heater we provide a shell 1 preferably of cylindrical form in an upright position, the lower end of the said shell being utilized to form a fire-box 2 provided with means for developing heat, for example, a gas burner 3. The upper side of the fire box 2 is nearly closed by a fire-box head 4, with a central opening carrying a flue 5 preferably of tubular form that extends upwardly and passes through the upper head 6 of the shell 1. Over the fire box head 4 is a water head 7 which is formed with a central opening carrying a tubular jacket 8 that surrounds the flue 5 and cooperates with the same to form an annular relatively narrow water jacket 9 communicating with the water space 10 that is formed between the heads 4 and 7. The heads 4 and 7 are preferably made of sheet metal and crowned in an upward direction so that their convex sides are disposed upwardly. They are formed with flanges 11 that may be welded to the inner side of the shell 1.

The tubular jacket 8 extends up to an elevated point in the tank or shell 1 and is preferably secured to an annular head or collar 12 secured to the flue just below the head 6. Preferably at an elevated point so as to be remote from the ebullition point in the heater we provide means of communication between the water jacket space or compartment 9 and the service water space 13 that is formed within the shell 1 and around the jacket 8. This may be accomplished in any suitable manner but we prefer to employ for this purpose, an opening 14 formed in the jacket just below the jacket head 12, that

is to say at a point that is remote from the fire box and the ebullition zone at the fire-box (see Fig. 1). This opening should not be so large as to permit circulation between the trapped water space and the space 13. We prefer to provide the flue 5 with means for increasing the temperature and transfer of heat at as low a point in the heater as possible. For this purpose we prefer to provide the interior of the flue 5 with a plurality of baffles 15 which may be of general fan shape (see Figure 2) and carried on a common central rod or stem 16.

If desired the shell 1 may be surrounded with lagging 17 of insulating material forming an insulating jacket between the shell 1 and an outer covering or shell 18. The heater may be provided with a sleeve 19 for the attachment of a thermostat control device.

From the above description, it will be evident that in practicing our invention, we provide a water compartment with trapped water therein, located between the flue and the service water compartment. It is also evident that, as the communication vent between the two water chambers is located remote from the fire-box and the ebullition zone, there will be very slight agitation of the trapped water in the vicinity of the vent, and a relatively small opening will suffice to relieve the pressure due to expansion without occasioning any substantial replacement of trapped water by service water.

In the operation of this heater it will be evident that although the opening 14 prevents any possibility of developing a higher pressure in the trap compartment 9 than in the service water compartment 13, nevertheless, the water in the trapped water compartment is substantially trapped, that is to say, the construction is such as to prevent free circulation between the trapped water compartment and the service compartment. Of course, if boiling occurs in the trapped water there is a tendency for a slight emission of water to occur at the opening 14 into the upper part of the chamber 13, but in this operation the baffles 15 cooperate to confine the highest temperature to a low level in the flue. In this way hot water rising in the jacket space 9 tends to have its temperature reduced before it reaches the opening 14. If any slight emission of water does occur from the jacket space 9, a replacement of this water would occur but such replacements are in such small quantities that they do not substantially increase the deposit of lime compounds in the trapped water space. The head 6 is provided with nipples 20 and 21, one of which would be an inlet and the other an outlet for the heated service water.

What we claim is:

1. In a water heater of the kind described, the combination of a shell having a service water chamber for the service water to be heated, a water inlet and a water outlet therefor, a fire box with a head in the lower part of the shell, a hot gas flue extending up from the said head for carrying up gases of combustion from the fire box, a water head mounted in the shell above the fire-box head and cooperating with the fire-box head and the shell to form a trapped water compartment over the fire-box head, a tubular jacket surrounding the said flue and connected to the water head so as to form a trapped water jacket around the flue communicating with the said water compartment, a cover head secured to the said shell, and means located remote from the ebullition point adjacent said fire-box head, for

maintaining pressure communication between the water jacket and the service water space within the said shell and operating to maintain equilibrium of pressures without circulation of water between the trapped water in the jacket and the service water being heated in the water space of the shell, said pressure communicating means being the sole means of communication between the water jacket and the service water compartment. 80 85

2. In a water heater of the kind described, the combination of a shell having a service water chamber for the service water to be heated, a water inlet and a water outlet therefor, a fire box with a fire-box head in the lower part of the shell, a hot gas flue extending up from the said head for carrying up gases of combustion from the fire-box, a water head mounted in the shell above the fire-box head and cooperating with the fire-box head and the shell to form a trapped water compartment over the fire-box head, a tubular jacket surrounding the said flue and connected to the water head so as to form a trapped water jacket around the flue communicating with the said water compartment, a cover head secured to the said shell with a restricted opening remote from the ebullition point at said fire-box head and adjacent the upper end of the tubular jacket and operating to maintain equilibrium of pressure without circulation between the water 100 105 in the jacket and the water space of the shell, said pressure communicating means being the sole means of communication between the water jacket and the service water compartment. 90 95

3. In a water heater of the kind described, the combination of a shell having a service water chamber for the service water to be heated, a water inlet and a water outlet therefor, a fire-box with a fire-box head in the lower part of the shell, a hot gas flue extending up from the said head 110 for carrying up gases of combustion from the fire-box, a water head mounted in the shell above the fire-box head and cooperating with the fire-box head and the shell to form a trapped water compartment over the fire-box head, a tubular jacket surrounding the said flue and connected to the water head so as to form a trapped water jacket around the flue communicating with the said water compartment, a cover head secured to the said shell, and means located remote from 115 the ebullition point of said fire-box head, for maintaining pressure equalization between the water jacket and the service water space within the said shell and operating to maintain equilibrium of pressure without circulation between the trapped water in the jacket and the service water being heated in the water space of the shell, said pressure communicating means being the sole means of communication between the water jacket and the service water compartment, 120 125 130 135 140

4. In a water heater of the kind described, the combination of a shell having a service water chamber for the service water to be heated, a fire box with a fire-box head in the lower part of the shell, a flue extending up from the said head for carrying up gases of combustion from the fire box, a water head mounted in the shell above the fire-box head and cooperating with the fire-box head and the shell to form a trapped water compartment over the fire-box head, a tubular jacket surrounding the said flue and connected to the 145 150

- water head so as to form a trapped water jacket around the flue communicating with the said water compartment, a cover head secured to the said shell, and means located at a high level 5 within the shell for maintaining communication between the water jacket and the service water space within the said shell and operating to maintain equilibrium of pressures between the trapped water in the jacket and the service water 10 being heated in the water space of the shell, said heater head and said water head being of crowned form with the convex side disposed upwardly and having flanges at their edges secured to said shell, and baffles carried within the flue for checking the outward flow of the gases of combustion, thereby increasing the temperature toward the lower part of the flue and jacket, and reducing the temperature of the trapped water in the upper part of the jacket. 15
- 20 5. In a water heater of the kind described, the combination of a shell having a service water chamber for the service water to be heated, a water inlet and a water outlet therefor, a head in the lower part of the shell, a flue extending up from the head for carrying up a heating gas, a water head mounted in the shell above the first named head and cooperating with the first named head and the shell to form a trapped water compartment over the first named head, a tubular jacket surrounding the said flue and connected to the water head so as to form a trapped water jacket around the flue communicating with the said water compartment, a cover head secured to the said shell and means located on the jacket 25 for maintaining pressure communication between the water jacket and the service water space within the shell and operating to maintain equilibrium of pressures without circulation of water between the trapped water in the jacket and the service water being heated in the water compartment of the shell, said pressure communicating means being the sole means of communication between the water jacket and the service water compartment. 30
- 35 40 45 6. In a water heater of the kind described, the combination of a vertically elongated shell having a service water compartment therein, an open inlet maintaining a constant supply of service water to the service compartment, an outlet connected with the service compartment only, a firebox at the lower end of the shell, a flue having its central axis at the axis of said shell, said heater having an annular wall and other walls cooperating with the annular wall and the flue to form a trapped water compartment with trapped water therein located between the flue and said service compartment, and means of communication between the water compartments located at a high level remote from the fire-box and the ebullition zone of the heater, operating to maintain pressure communication between the water compartments, said compartments being completely full during operation, said communication means being of relatively small area, said parts cooperating to heat the service water by the trapped water and said communication means operating to prevent substantial replacement of the trapped water by the service water during the operation of the heater, said communication means being the sole means of communication between said compartments. 50
- 55 60 65 70 75 80 85 90 95 100 105 110 115 120 125 130 135 140 145 150 155 160 165 170 175 180 185 190 195 200 205 210 215 220 225 230 235 240 245 250 255 260 265 270 275 280 285 290 295 300 305 310 315 320 325 330 335 340 345 350 355 360 365 370 375 380 385 390 395 400 405 410 415 420 425 430 435 440 445 450 455 460 465 470 475 480 485 490 495 500 505 510 515 520 525 530 535 540 545 550 555 560 565 570 575 580 585 590 595 600 605 610 615 620 625 630 635 640 645 650 655 660 665 670 675 680 685 690 695 700 705 710 715 720 725 730 735 740 745 750 755 760 765 770 775 780 785 790 795 800 805 810 815 820 825 830 835 840 845 850 855 860 865 870 875 880 885 890 895 900 905 910 915 920 925 930 935
7. In a water heater of the kind described, the combination of a vertically elongated shell having a service water compartment therein, an open inlet maintaining a constant supply of service water to the service compartment, an outlet connected with the service compartment only, a firebox at the lower end of the shell, a flue having its central axis at the axis of said shell, said heater having an annular wall and other walls cooperating with the annular wall and the flue to form a trapped water compartment with trapped water therein located between the flue and said service compartment, and means of communication between the water compartments located at a high level remote from the fire-box and the ebullition zone of the heater, operating to maintain pressure communication between the water compartments, said compartments being completely full during operation, said communication means being of relatively small area, said parts cooperating to heat the service water by the trapped water, and said communication means operating to prevent substantial replacement of the trapped water by the service water during the operation of the heater, said communication means being the sole means of communication between said compartments. 70

- a service water compartment therein, an inlet and an outlet connected with the service compartment only, a fire-box at the lower end of the shell, said heater having annular walls and other walls, 5 certain of said walls cooperating with certain of said annular walls to form a single flue extending from the fire-box and said walls forming a trapped water compartment with trapped water therein located between the flue and the service 10 water compartment, and means of communication between the water compartments located at a level remote from the fire-box and its adjacent zone of the heater, operating to maintain pressure communication between the water compartments, 15 said compartments being completely full during operation, said parts cooperating to heat the service water by the trapped water and said communication means cooperating with the other parts of the heater to prevent substantial replacement 20 of the trapped water by the service water during the operation of the heater, and being the sole means of communication between the said compartments.
11. In a water heater the combination of an upright cylindrical shell, a fire-box at the lower end of said shell, a plurality of annular upright walls within the shell, one of which forms a flue for carrying gases of combustion upwardly from the fire-box and other walls cooperating with the 25 annular walls to form a trapped water compartment for trapped water heated by the gases in said flue, and cooperating to form a service water compartment adjacent the trapped water compartment, an open inlet maintaining a constant supply 30 of service water to the service compartment, an outlet for delivering service water connected to the service compartment only, both of said compartments being completely full of water at all times during the operation of the heater, and 35 means of communication maintaining communication at all times between the water in the service compartment and the water in the trapped water compartment located at a level remote from said fire-box, all of said parts cooperating to impart heat from the trapped water to the service water, but preventing substantial replacement of the trapped water by service water during the operation of the heater.
